INVENTOR:
PERCY A. CAMPBELL,
BY Alexander S. Jones
His Attorney.

UNITED STATES PATENT OFFICE

PERCY A. CAMPBELL, OF EAST CLEVELAND, OHIO, ASSIGNOR TO GENERAL ELECTRIC COMPANY, A CORPORATION OF NEW YORK

INCANDESCENT-LAMP MOUNT

Application filed December 14, 1927. Serial No. 240,032.

My invention relates to electric incandescent lamps and similar devices comprising a filament which is inclosed in a bulb and is adapted to be heated to incandescence. More particularly my invention relates to the electrical connections between a coiled filament and its supports and to methods of manufacture thereof. My invention is particularly adapted to the mounting of coiled filaments for gas-filled lamps such as disclosed in Langmuir Patent No. 1,180,159, issued April 18, 1916. The object of my invention is to produce a joint between its filament and support which will be strong and minimize a tendency to arc and which, moreover, may be conveniently manufactured at comparatively low cost.

The practice has been to coil tungsten and like refractory metal filaments on copper, brass, nickel and other comparatively non-refractory mandrel wires. It has been the practice to afterwards dissolve out the mandrel completely by a suitable re-agent, usually an acid, which does not affect the tungsten. A mount has then been made by welding or otherwise uniting the ends of the filament to supports usually of nickel. According to my invention the ends of the coiled filament containing short lengths of a mandrel composed of the non-refractory metals are united to the filament support. This produces a much more secure joint and on account of the larger cross section, the temperature during the operation of the lamp is not nearly as high thereby reducing the percentages of failures of filaments at the joint. Moreover the avoidance of high temperature reduces the tendency to arc which is a trouble which frequently occurs between the leads in gas-filled lamps. Another feature of my invention is the method of manufacture. I have found that I can dissolve the portion of the mandrel contained within the intermediate portion of the filament leaving the end portions intact. This greatly simplifies the manufacture because the dissolving of the mandrel and the formation of the end mandrel supports is accomplished in one step.

In the drawings, Fig. 1 is an elevation of one form of electric incandescent lamp com-

prising a filament and support therefor embodying my invention; Fig. 2 is a similar view of another form of electric incandescent lamp and filament; Fig. 3 is a fragmentary elevation on an enlarged scale showing the connection between the filament and its support; Fig. 4 is a similar view of another form of filament and support; and Fig. 5 is a perspective view on an enlarged scale of a portion of a double coiled filament and its mandrels.

The incandescent electric lamps shown in Figs. 1 and 2 each comprise the usual bulb 10, base 11 and stem 12 in which are sealed the leading-in conductors 13-14. The conductive supports 15-16 project within the lamp and at their inner ends are connected to the filament which is supported thereby and by the anchors 17, 18 and 19 projecting from the glass rod 20 forming part of the stem 12. As shown in Fig. 3, the filament 21, ordinarily of tungsten, is first coiled upon a mandrel 22. The mandrel containing the coiled filament is then coiled upon a somewhat larger mandrel 23, and after completion, the coiled coil is then mounted upon the conductive supports 15-16. The joint between the said supports and filament is preferably made by percussive welding. The filament is then treated so that a portion of its mandrels contained within the intermediate portion thereof are dissolved out leaving the end portions intact. These mandrels may be composed of copper, brass, nickel or some other non-refractory metal. In Fig. 4 another form of filament is shown which is of an inverted U-shape and like the form shown in Fig. 3, has the short mandrel at its ends.

The method which I prefer to follow in the manufacture of lamps of this character is to coil the filaments on the full length of mandrel wire and then dissolve out a portion of the mandrel by an acid mixture such as four parts nitric acid to one part sulphuric acid or by any other solvent which will not affect the tungsten or other filament wire.

What I claim as new and desire to secure by Letters Patent of the United States, is:

1. In an electric incandescent lamp or similar device, the combination of a conductive

support and a coiled filament having therein at its end for a portion of its length a mandrel composed of non-refractory metal united to said support.

5 2. In an electric incandescent lamp or similar device, the combination of a pair of conductive supports and a coiled coil filament of refractory metal containing at each end thereof portions of mandrels composed of 10 non-refractory metal.

15 3. The method of manufacturing filaments for electric incandescent lamps and similar articles which comprises the coiling of a refractory metal filament on a mandrel of non-refractory metal and then dissolving out the mandrel from an intermediate portion of 20 said filament leaving a section of said mandrel at each end.

25 4. The method of manufacturing electric incandescent lamps which consists in coiling a refractory metal filament on a non-refractory mandrel, dissolving out a portion of said mandrel from the intermediate portion of 25 said filament, leaving sections of said mandrel at the ends of said filament and then uniting said ends to conductive filament supports to constitute the mount.

In witness whereof, I have hereto set my hand this 12th day of December, 1927.

30 PERCY A. CAMPBELL.
